UNITED STATES PATENT OFFICE.

OMER HEATH MAHAFFEY, OF EDMONTON, ALBERTA, CANADA.

CUE-TIP CHALKER.

Application filed June 16, 1924. Serial No. 720,411.

My invention relates to improvements in cue tip chalkers, and the object of the invention is to devise a simple device for holding chalk for chalking cue tips so that it will always be easily gotten at, in which there will be no danger of the holding string wearing out, in which the breaking of the pins holding the string is eliminated, in which sufficient holding string may be contained so that there will be no danger of the string being broken or the pins loosened by the jerking of the user upon the string during the operation of chalking, and in which means is provided whereby the winding mechanism can only be operated by the proprietor, and therefore cannot be tampered with by any other person, and it consists essentially of the arrangement and construction of parts hereinafter more particularly explained.

Fig. 1 represents a perspective view of my device.

Fig. 2 is a cross sectional view through Fig. 1.

Fig. 3 is a sectional view taken at right angles to Fig. 2 on line 3—3 looking in the direction of arrow.

Fig. 4 is a view in elevation looking in the direction of arrow Figure 2 from the line 30 4—4.

In the drawings like characters of reference indicate corresponding parts in each figure.

1 indicates a cylindrical casing provided 35 with heads 2 and 3 which are connected together by cross-bolts 4.

5 is a bracket by which the holder may be secured in position either beneath the billiard table or in any other suitable position. The casing 1 is provided with a circumferential slot 1* of sufficient width to permit the passage of a hand therethrough, the edges of which are turned inward, as indicated at 2*, so as to present a smooth edge 45 to contact with the holding string of the chalk holder.

6 is a stud shaft upon which is mounted a drum 7 upon which is wound a holding string 8, being secured at one end to the central core of the drum. The drum 7 is so positioned that the centre sleeve thereof is slightly below the lower peripheral portion of the forward edge of the slot 1* so as to permit the free passage of the cord or string 55 8 horizontally forward without frictionally

engaging the slot edge and thus become worn.

9 is a chalk container of the type commonly employed in which the chalk 10 is secured.

11 is a pinion mounted upon the stud 6 and formed integral with the drum 7.

12 is an arbor extending through the head 2 of the main casing and provided at its outer end with a squared portion 12*.

13 is a supplemental frame secured within the main frame preferably to the head 2, and in which is journalled the arbor 12. 14 is a helical spring secured at one end to the arbor 12 and at the opposite end to an 70 enclosing cylindrical casing 15.

16 are teeth or pins extending outward from one face of the casing 15, and with which a dog 17 engages to prevent the rotation of the casing in the direction of the 75 pull of the spring.

18 is a gear wheel secured to the arbor 12, and in mesh with the pinion 11.

19 is a key provided with an internal portion 19* with which the squared portion 80 12* of the arbor engages. The key 19 may be readily attached at any time by the proprietor on the operating end of the arbor 12, and the spring wound to the required tension, being held in its wound position 85 by the dog 17. When it is desired to chalk a cue, all that it is necessary to do is to pull the chalk retainer outward from the casing 1 to any extent desired, chalk the cue tip and then release the retainer so that the 90 spring 14 rotates the drum in a contrary direction to rewind the string 8 thereonto.

From this description it will be seen that I have devised a very simple device which will absolutely eliminate any danger of the 95 holding string being worn out during its operation, which will have a large string holding capacity, and therefore there will be no danger of the string running short and the holder being strained by the user of the 100 chalk holder jerking upon the string, and which at the same time will eliminate any danger of the spring being broken or the spring being loosened from a similar cause, and in which the mechanism will be entirely 105 under the control of the proprietor so that it cannot be tampered with by any other person.

What I claim as my invention is:

A cue tip chalker comprising a cylindrical 110

casing having a peripheral slotted opening in its lower portion, the ends of the slot extending in horizontal alignment and of sufficient width to permit the passage of the operator's hand, a shaft journaled in the casing a drum mounted on the shaft so that the lower peripheral portion of its centre sleeve is substantially slightly below the level of the forward end of the slot, a cord secured thereto and wound thereon, a chalk

holder secured to the free end of the cord, a supplemental shaft geared to the aforesaid shaft, a spring drive to such supplemental shaft, a ratchet wheel carried by the supplemental shaft, a dog coacting therewith, and a key member adapted to be detachably connected to the external end of the supplemental shaft. 15

OMER HEATH MAHAFFEY.
